2 SHEETS—SHEET 2.

UNITED STATES PATENT OFFICE.

ROBERT A. SALE, OF HIGH POINT, NORTH CAROLINA.

WAGON.

1,178,106.

Specification of Letters Patent. Patented Apr. 4, 1916.

Application filed October 19, 1911, Serial No. 855,486. Renewed February 26, 1916. Serial No. 80,763.

To all whom it may concern:

Be it known that I, ROBERT A. SALE, a citizen of the United States, residing at High Point, in the county of Guilford and State of North Carolina, have invented a new and useful Wagon, of which the following is a specification.

It is the object of this invention to provide, in a wagon, a novel form of skein which may be fashioned at small cost and from inexpensive materials, to be applied with a minimum effort, and having novel means whereby, at once, the skein will be prevented from rotating and the longitudinal edges of the skein will be prevented from separating; the skein being a tubular structure which is split longitudinally so that it may readily be wrapped around the axle.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings,—Figure 1 shows the invention in perspective; Fig. 2 is a longitudinal section, parts being broken away, and parts appearing in elevation; Fig. 3 is a sectional elevation of one of the axles; Fig. 4 is a plan of the blank which is employed in forming the axle bearings; Fig. 5 is a longitudinal section of the rear axle and the rear axle cap; Fig. 6 is a side elevation of the wheel; Fig. 7 is a transverse section of the wheel; Fig. 8 is a plan of the blank which is used in fashioning the bearing of the wheel, and in fashioning the bearing which is inserted into the forward end of the reach; Fig. 9 is a plan of the blank which is employed in fashioning the bearing for the front axle post; Fig. 10 is a sectional elevation of the front axle post, parts being broken away; and Fig. 11 is a fragmental perspective of the rear end of the tongue.

The device herein disclosed may be made in any size and may be adapted for many purposes. In the present instance, it is shown in the form of child's wagon of simple construction.

The wagon includes a body, denoted gen-

erally by the numeral 1, the body comprising a seat portion 2 and a narrow reach 3. In the lower face of the seat portion 2 of the body 1 there is a transverse groove 4, 60 adapted to receive a tongue 5, upstanding from the upper edge of the bolster 6. In the lower edge of the bolster 6 there is a groove 7, adapted to receive a tongue 8, upstanding from the upper edge of the axle 65 cap 9, the axle cap 9 being equipped in its lower edge with a depending tongue 10, adapted to register in a groove 11 in the upper edge of the axle 12 constituting a supporting element for the rear wheels. There 70 are aligned openings in the seat 2, in the bolster 6, in the axle cap 9 and in the axle 12, certain of these openings appearing in Fig. 5, and being there denoted by the numeral 14. Into these openings is inserted 75 a bolt 15 or other connecting element, carrying at its lower end a nut 16, adapted to hold the seat portion 2 of the body 1, the bolster 6, the axle cap 9 and the axle 12 together, so that their several tongues and 80 grooves will be maintained in interlocked relation.

Superposed upon and secured to the forward end of the reach 3 is a reinforcing block 17. There is an opening through the 85 reinforcing block 17 and through the forward end of the reach 3, and into this opening is inserted a tubular bearing denoted generally by the numeral 18. This bearing 18 is fashioned from a rectangular blank 19, 90 shown in Fig. 8. The blank 19 is rolled into tubular form, but its longitudinal edges are not connected in any manner. The tubular bearing thus formed, is inserted into the opening through the reinforcing block 17 95 and through the reach 3, the bearing being butt-ended in a machine. This operation will result in the blank yielding at its weakest points, to form slits 20 and tongues 21 in the end edges of the blank, the tongues 100 21 being beaten down flat upon the upper surface of the block 17 and upon the lower surface of the reach 3, as shown at 22.

The numeral 23 indicates generally, the forward axle constituting a supporting element for the forward wheels. Disposed rectangularly with respect to the axle 23 is an axle post or supporting element 24, the lower end of which is straddled upon the axle 23, as shown at 25, the post 24 and the 110 axle 23 being secured rigidly together. The upper end of the axle post 24 is reduced in

diameter to form a circular spindle 26, the upper end of which is flattened as shown at 27, and bifurcated. Through the flattened end 27 of the axle post an opening 28 extends.

The spindle 26 is surrounded by a tubular bearing, denoted by the numeral 29. This bearing 29 is fashioned from a blank 30, of rectangular contour, as shown in Fig. 9. 10 One of the shorter end edges of the blank 30 is equipped with a series of pointed teeth 31. The blank 30 is wrapped around the spindle 26 to form the bearing 29, the longitudinal edges of the blank 30 remaining 15 disconnected. One end of the bearing 29 is driven into the axle post proper 24, as shown at 32, the teeth 31 facilitating the driving operation, and also serving to prevent the bearing 29 from rotating upon the 20 spindle 26 of the axle post. A washer 33 rests upon the upper end of the axle post 24, about the spindle 26. The bearing 29 is inserted inside of the bearing 18, whereby the axle post 24 is rotatably assembled with the 25 forward end of the vehicle.

The tongue 34 may be equipped at its free end with a transverse handle 35, a bearing plate 36 being bent around the other end of the tongue. The bearing plate 36 is held 30 in place in any desired manner upon the tongue 34, and through the bearing plate 36 and through the tongue 34 there is an opening 37, adapted to be alined with the opening 28 in the bifurcations 27 of the spindle 26. A pivot pin 38 is inserted through the openings 28 and 37, to permit a tilting movement of the tongue 34.

Both of the axles 12 and 23 terminate in spindles 47, surrounded by tubular bearings 40. These bearings are fashioned from a flat metal blank 40, all of the bearing blanks being, of course, of metal. The blank 40, as shown in Fig. 4 is of rectangular contour. Upon one of its shorter end edges, a series 45 of pointed teeth 41 are formed. The blank 40 is rolled into tubular form and placed about the spindle 47, the longitudinal edges of the blank 40 being free and unconnected. The toothed end of the bearing thus constructed, is driven into the axle proper, as clearly shown in Fig. 3, the teeth 41 facilitating the driving operation, these teeth, moreover, serving to prevent the bearing 39 from rotating upon the spindle 47. During 50 the driving of the bearing 39 to place, the bearing will split as shown at 42 to form a series of tongues 43. The driving of the bearing will serve to beat the tongues 43 down flat upon the end of the spindle 47, as shown at 45. The numeral 44 indicates that end of the bearing which is thus inserted into the axle. The end of the axle proper, adjacent the spindle 47, is surrounded by a retaining band 46.

55 Each wheel consists of a wooden disk 48,

to the opposite faces of which wooden hubs 49 are applied. In fashioning the bearing 51 for the wheel, the blank 19, shown in Fig. 8, and hereinbefore described, is employed. This blank 19 is rolled into tubular 70 form, its longitudinal edges being free and unconnected. This tubular element is then inserted through the hubs 49 and through the disk 48, the tongues 21 being beaten down upon the outer faces of the hubs 49, as indicated at 50. Into the periphery of the disk 48, pins 52 are radially inserted. These pins 52 extend from a point adjacent the periphery of the wheel, into close relation to the bearing 51, the pins 52 being mounted in the 80 disk 48 at right angles to the grain of the wood from which the disk is fashioned. As will be readily understood, the pins 52 serve to prevent a splitting of the wheel.

When the wheels are mounted in place 85 upon the axle spindles, cotter pins or the like 53, are inserted through openings 54, extended through the bearings 39 and through the axle spindles 47.

Owing to the fact that the bearing 39 extends into the axle, as shown at 44, the axle is increased in strength at its weakest point, namely, the point where the spindle 47 merges into the axle proper. The strength of the axle is increased further, by reason 90 of the fact that the end of the axle is surrounded by the band 46. Moreover, owing to the fact that the bearing 29 is toothed at its inner end, the bearing cannot rotate upon the spindle 37, independently of the same. 100 The foregoing remarks apply with equal propriety to the construction of the bearing 29 which is mounted upon the spindle 26 of the axle post 24.

Considered generally, there is a marked 105 advantage in fashioning the bearings of the vehicle from the blanks 19, 30 and 40. Owing to the fact that these flat metal blanks are employed in fashioning the bearings, and owing to the fact that the longitudinal edges 110 of the blanks are not connected, the expense of providing a tubular bearing is avoided. Rotation of the blanks upon their inclosed spindles is prevented by the teeth, of which the elements 41 may be taken as typical. 115 The tongues 21 and 43 serve to house the ends of the spindles, and to maintain, in the case of the wheel, the bearing 51 assembled with the disk 48 and with the blocks 49.

In order to simplify the illustration, the 120 novel elements of the structure have been shown in connection with a small, inexpensive vehicle, but these details are applicable with equal propriety, to a vehicle of any size.

Having thus described the invention, what is claimed is:

1. In a device of the class described, a supporting element provided with a spindle; a bearing surrounding the spindle and hav- 125

ing its longitudinal edges free, the bearing being provided with teeth at one end, the toothed end of the bearing being inserted into the supporting element to prevent a 5 rotation of the bearing on the spindle and to prevent a separation of the edges of the bearing.

2. In a device of the class described, a supporting element provided with a spindle; 10 a bearing surrounding the spindle and having its longitudinal edges free, the bearing being provided with teeth upon one end, the toothed end of the bearing being driven into the supporting element; and a band surrounding 15 the supporting element in alignment with the teeth carrying end of the bearing.

3. In a device of the class described, a supporting element provided with a spindle; 20 a bearing surrounding the spindle and having its longitudinal edges free, one end of the bearing being inserted into the supporting element, and the other end of the bearing

being provided with a plurality of tongues, angularly disposed with respect to the axis 25 of the bearing, the tongues engaging the end of the spindle.

4. In a device of the class described, a supporting element provided with a spindle; 30 a bearing surrounding the spindle and having its longitudinal edges free, one end of the bearing being provided with teeth, the toothed end of the bearing being inserted into the supporting element, the bearing being provided at its other end with a plurality of tongues, the tongues being angularly disposed with respect to the axis of the bearing, and being engaged with the end of the spindle.

In testimony that I claim the foregoing 40 as my own, I have hereto affixed my signature in the presence of two witnesses.

ROBERT A. SALE.
